(57) **ABSTRACT**

An airtight closure mechanism for a reclosable pouch includes first and second complementary closure elements, the first closure element comprising a first interlocking profile and the second closure element comprising a complementary second interlocking profile. First and second sealing sections are disposed on respective complementary sides of the first and second interlocking profiles. The first sealing section includes a first protuberance having a first distal surface, a second protuberance having a second distal surface, and a sealing flange attached to and extending between the first and second distal surfaces of the first and second protuberances, respectively. The second sealing section includes a sealing member disposed on a base of the second closure element. The sealing member is located a distance from the second interlocking profile that places a distal surface thereof between the first and second protuberances when the first and second interlocking profiles are occluded. Additionally, when the first and second interlocking profiles are occluded, the distal surface urges against the sealing flange to form an airtight seal therebetween.

BACKGROUND OF THE INVENTION

1. Field of the Invention

The invention relates generally to an airtight closure mechanism for a reclosable pouch.

2. Description of the Background of the Invention

Thermoplastic pouch openings are frequently sealed using resealable closure assemblies. In addition, resealable closure mechanisms having a single pair of opposing elongate interlocking profiles that are occluded between a user's fingers to create a seal are known. Moreover, it is common to employ closure mechanisms having multiple pairs of elongate interlocking profiles when a stronger and more secure seal is desired.

Recently, efforts have been directed to developing improved closures for resealable packages. For example, one resealable closure mechanism has a first fastener profile that involves a first tape having a protrusion extending along the surface of the tape, and a second fastener profile that involves a second tape having a substantially C-shaped member extending along the surface of the tape. When the pouch is closed, front and back walls of the pouch are captured between the interlocked protrusion and C-shaped member.

Another closure assembly involves a slider-actuated closure mechanism where a thin pliable membrane gets captured between first and second interlockable profiles of the closure mechanism. The membrane may be initially connected to the tops of the profiles across a mouth of the bag such that two layers of membrane material are captured between the closure mechanism profiles. Additionally, the membrane forms a tamper proof hermetic seal in an unopened package that requires the membrane to be sliced open to allow access to the inside of the package.

In another closure assembly, interlocking rib and groove elements act to reclosably seal a pouch opening. A funnel-shaped bag is connected to inner walls of the pouch just below the rib and groove elements and when inverted, the funnel shaped bag may be disposed between the interlocking rib and groove elements.

An additional resealable closure assembly involves interlocking channels disposed along a pouch opening. A flexible strip extends along one side of the pouch up through the pouch and along the interlocking channel disposed on the side of the pouch. When the pouch is closed, the interlocking channels are pressed into each other with the flexible strip disposed between the interlocking channels.

In another closure assembly, a reclosable closure mechanism has a first profile and a second profile where the profiles have complementary bulbous members that interlock in a tight interference fit. The first profile is also provided with an

2

asymmetrical arrow-shaped member that is interlockable with a groove element on the second profile.

In yet another closure assembly, a permanently closing plastic profile fastener has male and female profiles. The male profile is generally arrow-shaped and the female profile has a pair of side jaws which define a groove therebetween. The male profile is restrained from entering the female profile by a frangible diaphragm disposed across ends of the jaws of the female profile. The diaphragm blocks access into the female profile until a predetermined level of force is applied to push the profiles together, thereby fracturing the diaphragm and allowing the male profile to enter.

An additional closure assembly involves first and second mutually interlocking profiles having two sets of interlocking members. In addition, the central portion has at least one profile with a collapsible member. When the first and second mutually interlocking profiles are joined, the collapsible member compresses against the other profile to create a seal.

20 SUMMARY OF THE INVENTION

In one aspect of the present invention, an airtight closure mechanism for a reclosable pouch includes first and second complementary closure elements, the first closure element comprising a first interlocking profile and the second closure element comprising a complementary second interlocking profile. First and second sealing sections are disposed on respective complementary sides of the first and second interlocking profiles. The first sealing section includes a first protuberance having a first distal surface, a second protuberance having a second distal surface, and a sealing flange attached to and extending between the first and second distal surfaces of the first and second protuberances, respectively. The second sealing section includes a sealing member disposed on a base of the second closure element. The sealing member is located a distance from the second interlocking profile that places a distal surface thereof between the first and second protuberances when the first and second interlocking profiles are occluded. Additionally, when the first and second interlocking profiles are occluded, the distal surface urges against the sealing flange to form an airtight seal therebetween.

In another aspect of the present invention, a reclosable pouch includes first and second pouch sidewalls sealed to one another to define an opening. A one-way valve is disposed on or in at least one of the first or second pouch sidewalls. An airtight closure mechanism includes first and second closure elements that include first and second interlocking profiles, and first and second sealing sections, respectively. The first closure element is attached to the first sidewall and the second closure element is attached to the second sidewall proximate the opening to define a pouch interior. The first and second sealing sections are disposed on respective pouch interior sides of the first and second interlocking profiles, and the first sealing section includes a first protuberance having a first distal surface, a second protuberance having a second distal surface, and a sealing flange attached to and extending across the first and second distal surfaces of the first and second protuberances, respectively. The second sealing section includes a sealing member disposed on a base of the second closure element and located a distance from the second interlocking profile that places a distal surface thereof between the first and second protuberances when the first and second interlocking profiles are occluded. When the first and second interlocking profiles are occluded, the sealing member urges against the sealing flange to form an airtight seal therebetween.

In another aspect of the present invention, a sealing section for an airtight closure mechanism includes first and second sealing sections disposed on respective complementary sides of first and second closure elements. The first sealing section includes a first protuberance having a first distal surface, a second protuberance having a second distal surface, and a sealing flange attached to and extending across from the first and second distal surfaces of the first and second protuberances, respectively. The second sealing section includes a sealing member disposed on the second closure element and located on a base of the second closure element so as to urge against the sealing flange attached to and extending across from the first and second protuberances when the first and second closure elements are occluded to form an airtight seal therebetween.

BRIEF DESCRIPTION OF THE DRAWINGS

FIG. 1 is an isometric view of a reclosable pouch;

FIG. 2A is an enlarged partial cross-sectional view of an airtight closure mechanism in a non-occluded state in accordance with one embodiment of the present invention taken generally along the lines 2-2 of FIG. 1;

FIG. 2B is an enlarged partial cross-sectional view of an airtight closure mechanism in an occluded state in accordance with the embodiment of the present invention depicted in FIG. 2A;

FIG. 3A illustrates an enlarged partial cross-sectional view of a second embodiment in a non-occluded state taken generally along the lines 2-2 of FIG. 1;

FIG. 3B illustrates an enlarged partial cross-sectional view of the embodiment depicted in FIG. 3A in an occluded state;

FIG. 4A is an enlarged partial cross-sectional view of a third embodiment of the present invention in a non-occluded state taken generally along the lines 2-2 of FIG. 1;

FIG. 4B illustrates an enlarged partial cross-sectional view of the embodiment depicted in FIG. 4A in an occluded state;

FIG. 5A is an enlarged partial cross-sectional view of a fourth embodiment taken generally along the lines 2-2 of FIG. 1; and

FIG. 5B is an enlarged partial cross-sectional view of a fifth embodiment taken generally along the lines 2-2 of FIG. 1.

Other aspects and advantages of the present invention will become apparent upon consideration of the following detailed description, wherein similar structures have similar reference numerals.

DETAILED DESCRIPTION

Referring to FIG. 1, a reclosable thermoplastic pouch 10 includes first and second sidewalls 11, 12 joined around three edges 5a-5c by heat sealing or other sealing method known in the art to define an opening 13. Alternatively, the bottom edge 5b may be a fold line between the first and second side walls 11, 12. A closure mechanism 14 extends from the first and second sidewalls 11, 12 proximate the pouch opening 13. The closure mechanism 14 and the first and second sidewalls 11, 12 define a pouch interior 7. When occluded, the closure mechanism 14 provides an airtight seal such that a vacuum may be maintained in the pouch interior 7 for a desired period of time, such as days, months, or years, when the closure mechanism is sealed fully across the opening 13. Protuberances, for example ridges 300, 302, may also be disposed on the inner surfaces 15, 17 of the respective first and second side walls 11, 12 proximate the opening 13 to provide increased traction in a convenient area for a user to grip, such as a gripping flange, when trying to open the sealed pouch 10.

In one embodiment, the pouch 10 may include a second opening 13a through one of the sidewalls 11, 12 covered by a valve 6, such as a check or one-way valve, to allow air to be evacuated from the pouch interior 7 and maintain a vacuum when the closure mechanism 14 has been sealed. As shown in FIG. 1, the valve 6 may be disposed on the second sidewall 12 spaced from the closure mechanism 14. When in an open state, the valve 6 provides a fluid path with fluid communication between the pouch interior 7 and an exterior of the pouch. Illustrative valves useful in the present invention include those disclosed in, for example, Newrones et al. U.S. Patent application publication No. 2006/0228057. Other valves useful in the present invention include those disclosed in, for example, Ser. Nos. 11/818,592, 11/818,586, and 11/818,591, each filed on the same day as the present application. Although not shown, in some embodiments an evacuation pump or device may be used to evacuate fluid from the pouch 10 through, for example, the valve 6 disposed in one of the side walls 11, 12, or in the closure mechanism 14 or one of the side edges 5a, 5b, 5c of the pouch. Illustrative evacuation pumps or devices useful in the present invention include those disclosed in, for example, Ser. No. 11/818,703 filed on the same day as the present application.

In one embodiment, the first and second sidewalls 11, 12 and/or the closure mechanism 14 are formed from thermoplastic resins by known extrusion methods. For example, the sidewalls 11, 12 may be independently extruded of thermoplastic material as a single continuous or multi-ply web, and the closure mechanism 14 may be extruded of the same or different thermoplastic material(s) separately as continuous lengths or strands. Illustrative thermoplastic materials include polypropylene (PP), polyethylene (PE), metallocene-polyethylene (mPE), low density polyethylene (LDPE), linear low density polyethylene (LLDPE), ultra low density polyethylene (ULDPE), biaxially-oriented polyethylene terephthalate (BPET), high density polyethylene (HDPE), polyethylene terephthalate (PET), among other polyolefin plastomers and combinations and blends thereof. Further, inner surfaces 15, 17 of the respective sidewalls 11, 12 or a portion or area thereof may, for example, be composed of a polyolefin plastomer such as an AFFINITY™ resin manufactured by Dow Plastics. Such portions or areas include, for example, the area of one or both of the sidewalls 11, 12 proximate and parallel to the closure mechanism 14 to provide an additional cohesive seal between the sidewalls when the pouch 10 is evacuated of fluid. One or more of the sidewalls 11, 12 in other embodiments may also be formed of air-impermeable film. An example of an air-impermeable film includes a film having one or more barrier layers, such as an ethylene-vinyl alcohol copolymer (EVOH) ply or a nylon ply, disposed between or on one or more of the plies of the sidewalls 11, 12. The barrier layer may be, for example, adhesively secured between the PP and/or LDPE plies to provide a multilayer film. Other additives such as colorants, slip agents, and antioxidants, including for example talc, oleamide or hydroxyl hydrocinnamate may also be added as desired. In another embodiment, the closure mechanism 14 may be extruded primarily of molten PE with various amounts of slip component, colorant, and talc additives in a separate process. The fully formed closure mechanism 14 may be attached to the pouch body using a strip of molten thermoplastic weld material, or by an adhesive known by those skilled in the art, for example. Other thermoplastic resins and air-impermeable films useful in the present invention include those disclosed in, for example, Tilman et al. U.S. Patent application publication No 2006/0048483.

Although not shown, one or both sidewalls, such as the second sidewall 12, may also be embossed or otherwise textured with a pattern, such as a diamond pattern, on one or both surfaces spaced between the bottom edge 5b and the closure mechanism 14, or a separate textured or embossed patterned wall may be used to provide flow channels (not shown) within the pouch interior 7. The flow channels may provide fluid communication between the pouch interior 7 and the valve 6 when fluid is being drawn through the valve 6. Illustrative flow channels useful in the present invention include those disclosed in Zimmerman et al. U.S. Patent application publication No. 2005/0286808 and Tilman et al. U.S. Patent application publication No. 2006/0048483. Other flow channels useful in the present invention include those disclosed in, for example, Ser. No. 11/818,584 filed on the same day as the present application.

The resealable bag or pouch described herein can be made by various techniques known to those skilled in the art including those described in, for example, Geiger, et al., U.S. Pat. No. 4,755,248. Other useful techniques to make a resealable pouch include those described in, for example, Zieke et al., U.S. Pat. No. 4,741,789. Additional techniques to make a resealable pouch include those described in, for example, Porchia et al., U.S. Pat. No. 5,012,561. Additional examples of making a resealable pouch as described herein include, for example, a cast post applied process, a cast integral process, and/or a blown process.

Referring to FIGS. 2A and 2B, the closure mechanism 14 comprises a first closure element 20 that includes a first interlocking profile 22a and a second closure element 24 that includes a complementary second interlocking profile 26a. The first closure element 20 may also include a third interlocking profile 22b and the second closure element 24 may include a complementary fourth interlocking profile 26b. The first closure element 20 and second closure element 24 are elongate and extend along the opening 13 of the pouch 10. FIG. 2A depicts the first and second closure elements 20, 24 in a non-occluded state while FIG. 2B shows the first and second closure elements 20, 24 in an occluded state. In this embodiment, the first closure element 20 is attached to an outer surface 16 of the second sidewall 12, and the second closure element 24 is attached to the inner surface 15 of the first sidewall 11. The first and second interlocking profiles 22a, 26a are shown in FIGS. 2A and 2B as female and male closure profiles, respectively, and the third and fourth interlocking profiles 22b, 26b are shown in FIGS. 2A and 2B as male and female closure profiles, respectively. However, the configuration and geometry of the interlocking profiles 22a, 22b, 26a, 26b or closure elements 20, 24 shown herein may vary.

In a further embodiment, one or both of the first and second closure elements 20, 24 may include one or more textured portions, such as a bump or crosswise groove in one or more of the interlocking profiles 22a, 22b, 26a, 26b in order to provide a tactile sensation, such as a series of clicks, as a user draws the fingers along the closure mechanism 14 to seal the closure elements across the opening. In another embodiment, all of the closure profiles 22a, 22b, 26a, 26b include textured portions along the length of each profile to provide tactile and/or audible sensations when closing the closure mechanism 14. Further, in some embodiments, a sealing material such as a polyolefin material or a caulking composition such as silicone grease may be disposed on or in the interlocking profiles 22a, 22b, 26a, 26b or closure elements 20, 24 to fill in any gaps or spaces therein when occluded. The ends of the interlocking profiles 22a, 22b, 26a, 26b or closure elements 20, 24 may also be welded or sealed by ultrasonic vibrations

as is known in the art. Illustrative interlocking profiles, closure elements, sealing materials, tactile or audible closure elements, and/or end seals useful in the present invention include those disclosed in, for example, Pawloski U.S. Pat. No. 4,927,474, Dais et al. U.S. Pat. Nos. 5,070,584, 5,478, 228, and 6,021,557, Tomic et al. U.S. Pat. No. 5,655,273, Sprehe U.S. Pat. No. 6,954,969, Kasai et al. U.S. Pat. No. 5,689,866, Ausnit U.S. Pat. No. 6,185,796, Wright et al. U.S. Pat. No. 7,041,249, Pawloski et al. U.S. Pat. No. 7,137,736, Anderson U.S. Patent Application Publication No. 2004/0091179, Pawloski U.S. Patent Application Publication No. 2004/0234172, Tilman et al. U.S. Patent Application Publication No. 2006/0048483, and Anzini et al. U.S. Patent Application Publication Nos. 2006/0093242 and 2006/0111226. Other interlocking profiles and closure elements useful in the present invention include those disclosed in, for example, U.S. patent application Ser. No. 11/725,120, filed Mar. 16, 2007, and Ser. Nos. 11/818,593 and 11/818,596 each filed on the same day as the present application. It is further appreciated that the interlocking profiles or closure elements disclosed herein may be operated by hand, or a slider (not shown) may be used to assist in occluding and de-occluding the interlocking profiles and closure elements.

As shown in FIGS. 2A and 2B, a first sealing section 25 is disposed on the first closure element 20 between the first and third interlocking profiles 22a, 22b, and includes a first protuberance 28 having a distal surface 30 and extending from an elongate first base 21 of the first closure element. A central axis 28a of the first protuberance 28 is located a distance X measured along the first base 21 from a line perpendicular to the base and through a distal end 29 of the first interlocking profile 22a. This spacing of the central axis 28a of the first protuberance 28 at distance X allows for proper securement of the first and the second closure elements 20, 24 and may range, for example, from greater than about 0.08 inches to less than about 0.20 inches. The first sealing section 25 also includes a second protuberance 32 having a distal surface 34 and extending from the elongate first base 21 of the first closure element 20. A central axis 32a of the second protuberance 32 is located a distance Y measured along the first base 21 from a line perpendicular to the base and through the distal end 29 of the first interlocking profile 22a. In this embodiment, the distance Y is greater than the distance X, and the difference is represented by distance Y'. Illustratively, the distance Y' between the central axes 28a and 32a allows for a sealing flange 39 to extend from and across the distal surfaces 30, 34 of the first and second protuberances 28, 32, respectively. In this embodiment, the sealing flange 39 is integral with the second pouch sidewall 12, and in other embodiments the sealing flange 39 is a separate piece of thermoplastic film.

A second sealing section 27 is disposed on the second closure element 24 between the second and fourth interlocking profiles 26a, 26b, and includes a sealing member 36 having a distal surface 38. In this embodiment, the distal surface 38 is disposed at an apex of a third protuberance 137 that extends from an elongate second base 23 of the second closure element. Although in this embodiment the third protuberance 137 is disposed at an angle of less than 90 degrees relative to the second base 23, it is also contemplated that the third protuberance may be disposed at angles of approximately 90 degrees or greater than 90 degrees. However, by having the third protuberance 137 at a non-90 degree angle, the force necessary to urge the sealing member 36 and the sealing flange 39 together may be less due to the flexibility of the third protuberance as force is applied thereto while the first and second closure elements 20, 24 are being occluded. This flexibility increases as the angle increases past 90

degrees or decreases to less than 90 degrees, and may in some instances assist in maintaining an airtight seal with the sealing flange 39. A central axis 36a of the distal surface 38 of the sealing member 36 is located a distance Z measured along the first base 21 from a line perpendicular to the base and through the distal end 29 of the first interlocking profile 22a when the closure elements 20 and 24 are occluded. In this embodiment, the central axis 36a of the distal surface 38 does not correspond to a central axis (not shown) of the third protuberance 137. The distance Z ranges between the distances X and Y in this embodiment, such that the central axis 36a is disposed between opposing outer edges 35, 37 of the distal surfaces 30, 34, respectively in the occluded state, as shown in FIG. 2B.

When the closure elements 20, 24 are urged together the first interlocking profile 22a interlocks with the second interlocking profile 26a, and the third interlocking profile 22b interlocks with the fourth interlocking profile 26b. In this embodiment, because the sealing flange 39 is integral with the second pouch sidewall 12, the third and fourth interlocking profiles 22b, 26b interlock with the sealing flange trapped therebetween. In other embodiments, the sealing flange 39 may be made of a thermoplastic film independent of the sidewalls 11, 12 such as, for example, an elastomer or a polyolefin plastomer such as an AFFINITY™ resin manufactured by Dow Plastics, and the third and fourth interlocking profiles 22b, 26b may interlock without the sealing flange trapped therebetween. Additionally, in the occluded state, the first protuberance 28 interlocks with an asymmetrically-hooked protuberance 31 that extends from the elongate second base 23 of the second closure element 24. Although the first and second protuberances 28, 32 are illustrated in FIGS. 2A and 2B as T-shaped protuberances and a post shape is shown for the sealing member 36, other shapes may also be used, including for example, bulbous members, arrow or half-arrow shaped members, or rectangular, square-shaped, round, or triangular-shaped protrusions, as well as any combination thereof.

In another embodiment illustrated in FIGS. 3A and 3B, a closure mechanism 41 includes a first closure element 40 having a first interlocking profile 42a and a second closure element 44 having a complementary second interlocking profile 46a. The first closure element 40 may also include a third interlocking profile 42b and the second closure element 44 may include a complementary fourth interlocking profile 46b. FIG. 3A depicts the first and second closure elements 40, 44 in a non-occluded state while FIG. 3B shows the first and second closure elements 40, 44 in an occluded state. In this embodiment, the first closure element 40 is attached to the inner surface 17 of the second sidewall 12 and the second closure element 44 is attached to the inner surface 15 of the first sidewall 11. Illustratively, the first and fourth interlocking profiles 42a, 46b are shown as female and the second and third interlocking profiles 46a, 42b are shown as male closure profiles, however, the configuration and geometry of the interlocking profiles 42a, 42b, 46a, 46b or closure elements 40, 44 may vary as described previously herein. A first sealing section 47 extends from an elongate first base 43 of the first closure element 40 and contains a first protuberance 48 and a second protuberance 54 each having one or more sidewalls that extend substantially perpendicularly from the elongate first base 43. The first protuberance 48 has a distal surface 50 and a central axis 48a located a distance XX measured along the first base 43 from a line perpendicular to the base and through the distal end 53 of the first interlocking profile 42a. The second protuberance 54 has a distal surface 56 and a central axis 54a of the second protuberance 54 is located a distance YY measured along the first base 43 from a line

perpendicular to the base and through the distal end 53 of the first interlocking profile 42a. In this embodiment, the distance YY is greater than the distance XX, and the difference is represented by distance YY'. A second sealing section 49 includes a sealing member 58 having a distal surface 60 disposed at an apex of a third protuberance 158 that extends similar to that as shown in FIGS. 2A and 2B at an angle of less than 90 degrees from an elongate second base 45 of the second closure element 44. The sealing member 58 has one or more sidewalls that extend substantially parallel to one another from the elongate second base 45. A central axis 58a of the distal surface 60 of the sealing member 58 is located a distance ZZ measured along the first base 43 from a line perpendicular to the base and through the distal end 53 of the first interlocking profile 42a when the closure elements 40 and 44 are occluded. In this embodiment, the central axis 58a of the distal surface 60 does not correspond to a central axis (not shown) of the third protuberance 158. A sealing flange 66 extends across and is attached to the distal surface 50 of the first protuberance 48 and the distal surface 56 of the second protuberance 54. In this embodiment, the sealing flange 66 may be made of a thermoplastic film independent of the sidewalls 11, 12 such as, for example, an elastomer or a polyolefin plastomer such as an AFFINITY™ resin. However, in other embodiments, the sealing flange 66 may be made of one of the sidewalls 11, 12 or of the same or similar material(s). When the first closure element 40 and the second closure element 44 are urged together, as shown in FIG. 3B, the first interlocking profile 42a interlocks with the second interlocking profile 46a and the third interlocking profile 42b interlocks with the fourth interlocking profile 46b. In the occluded state, the sealing member 58 is urged against the sealing flange 66 to form an airtight seal therebetween.

Referring to FIGS. 4A and 4B, the closure mechanism 81 includes a first closure element 80 that has a first interlocking profile 82 and a second closure element 84 that includes a complementary second interlocking profile 86. FIG. 4A depicts the first and second closure elements 80, 84 in a non-occluded state while FIG. 4B shows the first and second closure elements 80, 84 in an occluded state. In this embodiment, the first closure element 80 is attached to the outer surface 16 of the second sidewall 12, and the second closure element 84 is attached to an outer surface 19 of the first sidewall 11.

A first sealing section 87 disposed on the first closure element 80 includes a first protuberance 98 having a distal surface 100 and extending from an elongate first base 83 of the first closure element. A central axis 98a of the first protuberance 98 is located a distance T measured along the first base 83 from a line perpendicular to the base and through a distal end 93 of the first interlocking profile 82. The first sealing section 87 also includes a second and third protuberance, 108, 110 respectively positioned on either side of the first protuberance 98. The second and third protuberances 108, 110 extend from the elongate first base 83 of the first closure element 80 and have respective distal surfaces 109, 114. A second sealing section 89 disposed on the second closure element 84 includes a first sealing member 88 having a distal surface 90 disposed at an apex of a fourth protuberance 188 that extends approximately 90 degrees or perpendicularly from an elongate second base 85 of the second closure element. A central axis 88a of the distal surface 90 generally corresponds in this embodiment to that of the first sealing member 88 and is located a distance R measured along the first base 83 from a line perpendicular to the base and through the distal end 93 of the first interlocking profile 82 when the closure elements 80 and 84 are occluded. The

second sealing section 89 further includes a second sealing member 94 having a distal surface 96 that is disposed at an apex of a fifth protuberance 194 and also extends approximately 90 degrees or perpendicularly from the elongate second base 85 of the second closure element 84. A central axis 94a of the distal surface 96 also generally corresponds to that of the second sealing member 94 and is located a distance S measured along the first base 83 from a line perpendicular to the base and through the distal end 93 of the first interlocking profile 82 when the closure elements 80 and 84 are occluded. In this embodiment, the distance S is greater than the distance T, which is greater than the distance R. Although both of the first and second sealing members 88, 94 have generally perpendicularly disposed respective fourth and fifth protuberances 188, 194, it is also contemplated that one or both may be disposed at an angle less than 90 degrees. The first closure element 80 may also include a third interlocking profile (not shown) on a product side of the first sealing section 87, and the second closure element 84 may include a complementary fourth interlocking profile (not shown) on the product side of the second sealing section 89.

A sealing flange 106 is attached respectively to the distal surfaces 100, 109, 114 of the first, second, and third protuberances, 98, 108, 110, respectively. In this embodiment, the sealing flange 106 is a part of the second sidewall 12. However, in other embodiments, the sealing flange 106 may be made of a thermoplastic film independent of the sidewalls 11, 12 such as, for example, an elastomer or a polyolefin plastomer such as an AFFINITY™ resin. The sealing flange 106 also includes a slit along a length thereof to form film flaps 112 to allow penetration of the first and second sealing members 88, 94 into spaces between the first protuberance 98 and the second protuberance 108 and the first protuberance 98 and the third protuberance 110, respectively, when the first closure element 80 and second closure element 84 are occluded. In the occluded state shown in FIG. 4B, the film flaps 112 are urged against respective surfaces of the first, second, third, fourth, and fifth protuberances 98, 108, 110, 188, 194 to form airtight seals between the first and second sealing members 88, 94 and the sealing flange 106. However, in other embodiments not shown, the first and second sealing members 88, 94 may be further spaced from the respective first, second, and third protuberances 98, 108, 110. In these embodiments, the film flaps 112 form an airtight seal with the first and second sealing members 88, 94 and have little or no contact with the respective surfaces of the first, second, and third protuberances 98, 108, 110. In FIGS. 4A and 4B, the sidewalls of the first through fifth protuberances 98, 108, 110, 188, 194 are substantially parallel and perpendicular relative to the elongate first and second bases 83, 85, but it is contemplated that any angle or shaped wall including straight, curved, arched, or serpentine, for example, may be used.

Referring to FIGS. 5A and 5B, a first closure element 120 is attached to the outer surface 16 of the second sidewall 12 and a second closure element 122 is attached (not shown) either to the inner or outer surfaces 15, 17 of the first sidewall 11. A first sealing section 121 includes a first protuberance 124 having a distal surface 126, a second protuberance 128 having a distal surface 130, and a third protuberance 132 having a distal surface 134, wherein each of the protuberances 124, 128, 132 extends from an elongate first base 136 of the first closure element 120. A second sealing section 123 includes a first sealing member 138 having a distal surface 144 and a second sealing member 140 having a distal surface 146, wherein each of the first and second sealing members 138, 140 extends approximately perpendicularly or about 90 degrees from an elongate second base 142 of the second

closure element 122. A sealing flange 148 extends across and is attached to the distal surfaces 126, 130, 134 of the first, second, and third protuberances 124, 128, 132 respectively. In the occluded state, each of the first and second sealing members 138, 140 is urged against the sealing flange 148 to form an airtight seal therebetween. In this embodiment, the sealing flange 148 is a part of the second sidewall 12. However, in other embodiments, the sealing flange 148 may be made of a thermoplastic film independent of the sidewalls 11, 12 such as, for example, an elastomer or a polyolefin plastomer such as an AFFINITY™ resin.

In FIG. 5A, each sealing member, 138, 140 has a respective fourth and fifth protuberance 238a, 240a that each has a width of W'. In FIG. 5B, each of the fourth and fifth protuberances 238b, 240b has a width of W''. The increased width (W'') of each of the fourth and fifth protuberances 238b, 240b in FIG. 5B relative to each of the fourth and fifth protuberances 238a, 240a of width W' in FIG. 5A results in an increased surface area upon which to contact the sealing flange 148. The increase in surface area results in a larger portion of the sealing flange 148 being contacted by the first and second sealing members 138, 140 in the occluded state, which may enhance sealing performance. Other ways to enhance sealing performance, include, for example, creating a tighter interference fit between the sealing flange 148 and one or more of the sealing members such as the first and second sealing members 138, 140. Illustratively, this can be achieved by increasing the length of the fourth or fifth protuberances 238a, 238b, or 240a, 240b, or the length of one or more of the first, second, or third protuberances 124, 128, 132. When the respective closure elements 120, 122 are urged together and become occluded, greater force may be required to occlude the closure elements due to a greater force required to urge the first and second sealing members 138, 140 and the sealing flange 148 together to form an airtight seal. Still other ways to enhance sealing performance, include, for example, using a thicker web or using multiple plies of material (not shown) to form a thicker sealing flange 148, or using a more resilient material to create a tighter interference fit between the first and second sealing members 138, 140 and the sealing flange.

Although the present invention has been described relative to specific exemplary embodiments thereof, it will be understood by those skilled in the art that modifications can be made thereto without departing from the scope and spirit of the invention.

INDUSTRIAL APPLICATION

An airtight closure mechanism is presented that may be used to pack and store perishable items in an airtight or vacuum environment. The closure mechanism includes first and second closure elements, wherein each of the closure elements has interlocking and sealing sections. A sealing flange is attached across the sealing section of one of the first and second closure elements, and the other of the first and second closure elements includes a sealing member. When the first and second closure elements are occluded, the sealing member is urged against the sealing flange and forms an airtight seal therebetween.

Numerous modifications to the present invention will be apparent to those skilled in the art in view of the foregoing description. Accordingly, this description is to be construed as illustrative only and is presented for the purpose of enabling those skilled in the art to make and use the invention and to teach the best mode of carrying out same. The exclusive rights to all modifications which come within the scope of the appended claims are reserved. All patents, patent pub-

11

lications and applications, and other references cited herein are incorporated by reference herein in their entirety.

We claim:

1. An airtight closure mechanism for a reclosable pouch, comprising:

first and second complementary closure elements, the first closure element comprising a first interlocking profile and the second closure element comprising a complementary second interlocking profile; and

first and second sealing sections disposed on respective

complementary sides of the first and second interlocking profiles, the first sealing section comprising a first protuberance having a first distal surface, a second protuberance having a second distal surface, and a sealing flange attached to and extending between the first and second distal surfaces of the first and second protuberances, respectively, and the second sealing section comprising a sealing member disposed on a base of the second closure element and located a distance from the second interlocking profile that places a distal surface thereof between the first and second protuberances when the first and second interlocking profiles are occluded; wherein when the first and second interlocking profiles are occluded, the distal surface urges against the sealing flange to form an airtight seal therebetween.

2. The airtight closure mechanism of claim 1, wherein the first and second closure elements are elongate and disposed along an opening of the pouch, and one or more of the closure profiles includes a textured portion along the length of each profile to provide tactile and/or audible sensations when the closure mechanism is occluded.

3. The airtight closure mechanism of claim 1, wherein the first closure element is attached on an outer surface of a first pouch sidewall and the second closure element is attached to an inner surface of a second pouch sidewall.

4. The airtight closure mechanism of claim 3, wherein the sealing flange comprises the first pouch sidewall.

5. The airtight closure mechanism of claim 1 further comprising a third protuberance disposed on the second closure element and adapted to releasably interlock with the first protuberance when the first and second interlocking profiles are occluded.

6. The airtight closure mechanism of claim 5, wherein the third protuberance comprises a hook portion to releasably interlock with the first protuberance.

7. The airtight closure mechanism of claim 1, wherein the first interlocking profile and the first protuberance are integral.

8. The airtight closure mechanism of claim 1, wherein the sealing flange comprises a slit disposed therein to allow penetration of the distal surface into a space between the first protuberance and the second protuberance when the first and second closure elements are occluded.

9. The airtight closure mechanism of claim 1, wherein the first and second protuberances independently comprise a post, a bulbous member, a T-shaped member, an arrow or half-arrow shaped member, or a rectangular, square-shaped, round, or triangular-shaped protrusion.

10. The airtight closure mechanism of claim 1, wherein the first and second interlocking profiles are female and male closure profiles, respectively.

11. A reclosable pouch, comprising:

first and second pouch sidewalls sealed to one another to

define an opening;

a one-way valve disposed on or in at least one of the first or

second pouch sidewalls;

12

an airtight closure mechanism comprising first and second closure elements that include first and second interlocking profiles, and first and second sealing sections, respectively;

5 the first closure element attached to the first sidewall and the second closure element attached to the second sidewall proximate the opening to define a pouch interior; and

the first and second sealing sections disposed on respective pouch interior sides of the first and second interlocking profiles, the first sealing section comprising a first protuberance having a first distal surface, a second protuberance having a second distal surface, and a sealing flange attached to and extending across the first and second distal surfaces of the first and second protuberances, respectively, and the second sealing section comprising a sealing member disposed on a base of the second closure element and located a distance from the second interlocking profile that places a distal surface thereof between the first and second protuberances when the first and second interlocking profiles are occluded; wherein when the first and second interlocking profiles are occluded, the sealing member urges against the sealing flange to form an airtight seal therebetween.

25 **12. The pouch of claim 11, wherein one or more of the closure profiles includes a textured portion along the length of each profile to provide tactile and/or audible sensations when the closure mechanism is occluded.**

30 **13. The pouch of claim 11, wherein at least one of the pouch sidewalls comprises air channels in fluid communication with the valve.**

14. The pouch of claim 11, wherein at least one or more of the first and second pouch sidewalls comprises a barrier layer.

35 **15. The pouch of claim 14, wherein the barrier layer comprises EVOH.**

16. An airtight sealing section for a closure mechanism, comprising:

first and second sealing sections disposed on respective complementary sides of first and second closure elements, the first sealing section comprising a first protuberance having a first distal surface, a second protuberance having a second distal surface, and a sealing flange attached to and extending across from the first and second distal surfaces of the first and second protuberances, respectively, and the second sealing section comprising a sealing member disposed on the second closure element and located on a base of the second closure element so as to urge against the sealing flange attached to and extending across from the first and second protuberances when the first and second closure elements are occluded to form an airtight seal therebetween.

17. The airtight sealing section of claim 16, wherein the sealing flange comprises the first pouch sidewall.

55 **18. The airtight sealing section of claim 16, wherein the sealing flange comprises a slit disposed therein to allow penetration of the sealing member into a space between the first protuberance and the second protuberance when the first and second closure elements are occluded.**

19. The airtight sealing section of claim 16, wherein at least one of the first or second closure elements are attached to an exterior side of a pouch wall.

20. The airtight sealing section of claim 16, wherein the sealing flange comprises at least one of an elastomer or polyolefin plastomer layer.
